EXPLOSION-MOTOR.

1,083,433.

Specification of Letters Patent.

Patented Jan. 6, 1914.

Application filed April 20, 1910. Serial No. 556,463.

To all whom it may concern:

Be it known that I, MARK B. CRIST, a citizen of the United States, and a resident of Pittsburgh, in the county of Allegheny and State of Pennsylvania, have made a new and useful Invention in Explosion-Motors, of which the following is a specification.

This invention relates to the general class of explosion motors and particularly to that class in which the explosion charge consists of air and gas.

As is well known, gases of different B. T. U. values require different proportions of air to effect proper combustion. For example, the proportions of producer gas to air is generally about 1 to 1 while the proportions of natural gas to air is about 1 to 13. The proportioning of air and gas for the combustion fuel may be provided by arranging different port cuttings in a piston admission valve whose ports communicate with the air and gas inlets, and the proper proportions will be maintained so long as the value of the gas remains constant. If however, as might easily be the case where producer gas was used, the B. T. U. value of the gas falls off, the relative proportions of air and gas entering the combustion chamber would be destroyed because as the gas becomes poorer the percentage of air to gas should be decreased and as the gas becomes richer again the relative proportion of air to gas should be increased.

I have provided means for maintaining the ignition fuel mixture in proper proportions of air and gas irrespective of variations in the quality of the gas during the operation of the engine, so that should the gas decrease in quality, a greater proportion of gas may be admitted as part of the mixture than would be admitted when the gas was rich. Instead of throttling the gas the air may be throttled, or if desirable, the air and gas could be throttled simultaneously; that is, more air admitted at the same time that less gas was admitted or vice versa.

In the drawings I have shown a cross-sectional view through a gas engine cylinder equipped with a mixing valve constructed in accordance with my invention and a throttling regulator, as shown in vertical

section as applied to the gas inlet pipe, which carries one of the mixture contents. 55

By referring to the drawings by numerals of reference, 1 designates a gas engine cylinder provided with the usual exhaust valve 2. The cylinder is shown as being provided with an inlet port 3 having a mixing valve 4 comprising a casing 4 provided with gas ports 5 and air ports 6. Within the casing 4 is a reciprocatory piston or trunk valve 7 having gas and air ports designated by the reference numerals 5^a and 6^a respectively and adapted to register with the gas and air ports in the casing 4. The valve 7 is carried by the stem 8 of a mushroom valve 9 which normally closes port 3 but the movement of which is synchronous with that of the valve 7. The valve stem 8 carries a head or disk 10 which is spring pressed so as to normally keep the valve 9 closed and consequently the valve 7 closed. The valves 7 and 9 are intermittently moved in opening directions by a rocking lever 11 shown as fulcrumed at 12 and actuated by rod 13 from some suitable shaft in a well known manner. On the shaft 8 is shown an arm 14 adapted to be connected to a governor or speed responsive device whereby a change in load will rotate the valve 7 about the valve stem 8 and throttle the charge. When the lever 11 is caused to effect an inward movement of the valves 7 and 9 the ports 5 and 6 are opened and the proper quantity of air and gas will be admitted to the combustion chamber, and if the quality of the gas is such as to be proper for the port cuttings 5 and 5^a the proper proportions of air and gas will be admitted but should the quality of the gas fall off or increase, the port cuttings 5 and 5^a would not provide proper proportions of air and gas for the best combustion. 95

I have provided means for overcoming the objection just enumerated and an embodiment of the device illustrated consists of a butterfly valve 15 in the supply pipe 16. A link 17 connected to said valve 15 is also connected to a link 18 which in turn is connected to a lever 19 fulcrumed at 20 on a bracket 21 on the stationary element 22 of a pressure regulator illustrated as a gasometer. The stationary element or tank 22 is in communication with the cylinder 1.

tion with the pipe 16 through a pipe 23 so that the pressure within the movable element or bell 24 of the gasometer will be dependent upon the pressure in the pipe 16. The movable member or bell 24 of the gasometer is connected to the lever 19 by link 25 so any movement of the lever 19 which will impart movement to the link 18 will likewise impart movement to the link 25 and therefore move the bell 24. An adjusting mechanism is provided for the gasometer which is illustrated as comprising a spring 26 connected to the lever 19 on the side of the fulcrum 20 opposite to that on which the links 18 and 25 are. The spring 26 is connected to a threaded pin 27 passing through an internally threaded adjusting wheel 28 carried by the bracket 29 on the gasometer tank 22, thus the gasometer bell 24 may be loaded to suit any pressure. Supposing for example that port cuttings of the admission valve were provided for producer gas, that is, the proportions of air and gas entering the combustion chamber were about 1 to 1. Under normal conditions, that is, so long as the gas remains constant in B. T. U. value, the relative proportions of air and gas entering the combustion chamber during constant load would remain the same. Should the gas fall off however in B. T. U. value the engine would slow down, the speed responsive device would open the valve 7 and there would be a pressure drop in the pipe 16 so that the bell 24 would drop against the action of the spring 26, and the valve 15 would be opened to permit a greater flow through the pipe 16. As the rate of flow (on account of the increase in pressure) would be increased through the ports 5 and 5^a, it is obvious that more gas would be admitted in proportion to the air. Should the B. T. U. value of the gas increase the pressure in the bell 24 would increase and the bell would be raised to throat the port through the medium of the valve 15, and the pressure in the pipe 16 would be cut down, therefore the proportion of gas to air would be decreased as the rate of flow of the gas would be decreased on account of the reduction of pressure in the pipe 16.

From the foregoing it will be obvious that the pressure regulator in connection with a valve of different port cutting will provide the proper proportions of air and gas irrespective of the change in B. T. U. value of

the gas and the proper adjustment for any predetermined pressure may be manually made through the medium of the adjusting wheel 28.

60

Having thus described my invention, what I claim is:

1. In a gas engine the combination with a valve having air and gas inlet ports, means for varying the port areas, air and gas conduits leading to said ports, a valve in one of said conduits, and a pressure regulator responsive to pressure due to the changes in the port areas of said first mentioned valve for operating said second mentioned valve.

65

2. In a gas engine, a valve having differently proportioned air and gas ports, air and gas conduits leading to said air and gas ports, means for varying the size of the port areas, and pressure regulated means for varying the pressure in one of said conduits responsive to pressure due to changes in the port areas.

75

3. In an internal combustion engine, a valve having air and gas ports, conduits leading to said air and gas ports, means for varying the port areas, a pressure regulator in communication with one of said conduits and responsive to pressure due to changes in the port areas of said first mentioned valve, a valve in one of said conduits, and means connecting the last mentioned valve to said pressure regulator whereby said pressure regulator will operate the last mentioned valve.

80

4. In an internal combustion engine, a valve having air and gas ports, air and gas conduits in communication with said ports, means for varying the port areas, a valve in one of said conduits, a pressure regulator in communication with one of said conduits and responsive to pressure due to changes in the port area of the port with which it communicates, means for connecting said pressure regulator to said valve, and means for adjusting said pressure regulator to operate under predetermined pressure, said pressure being determined to accommodate a gas of a known value.

90

In testimony whereof, I have hereunto subscribed my name this 18th day of April, 1910.

MARK B. CRIST.
